CLAIM

The ornamental design for steering wheel, as shown and described.

DESCRIPTION

FIG. 1 is a perspective view of a steering wheel showing our new design;

FIG. 2 is a left side elevational view thereof;

FIG. 3 is a front elevational view taken at 3—3 thereof;

FIG. 4 is a front elevational view taken at 4—4 thereof;

FIG. 5 is a top plan view taken perpendicularly of 3—3 and 4—4 thereof; and,

FIG. 6 is a rear elevational view thereof.

The broken lines shown in the FIGS. 1, 2 and 6 drawing views are for illustrative purposes only and form no part of the claimed design.
